UNITED STATES PATENT OFFICE

92,345

DESIGN FOR A LIGHTING FIXTURE BRACKET OR SIMILAR ARTICLE

Roscoe C. Gregg, Fredericktown, Ohio

Application March 14, 1934, Serial No. 51,044

Term of patent 3½ years

To all whom it may concern:

Be it known that I, ROSCOE C. GREGG, a citizen of the United States, residing at Fredericktown, in the county of Knox and State of Ohio, have invented a new, original, and ornamental Design for a Lighting Fixture Bracket or Similar Article, of which the following is a specification, reference being had to the accompanying drawing, forming a part thereof.

Fig. 1 is a perspective view of a lighting fixture bracket or similar article showing my new design;

Fig. 2 is a top plan view thereof.

I claim:

The ornamental design for a lighting fixture bracket or similar article, as shown.

ROSCOE C. GREGG.
